UNITED STATES PATENT OFFICE.

DOD HASLUP, OF GRAFTON, WEST VIRGINIA.

DESIGN FOR A NECKTIE-HOLDER.

SPECIFICATION forming part of Design No. 31,394, dated August 15, 1899.

Application filed July 20, 1899. Serial No. 724,562. Term of patent 14 years.

To all whom it may concern:

Be it known that I, DOD HASLUP, a citizen of the United States, residing at Grafton, in the county of Taylor and State of West Virginia, have invented and produced a new and original Design for a Necktie-Holder, of which the following is a specification.

The invention relates to a new and original design for necktie-holders; and it has for its object to provide a design of this character which will be both ornamental and useful.

The essential feature of the design resides in a plate or body of substantially oblong shape provided at its ends with tapering tongues or projections and having at a point between its ends a transversely-disposed arm or hook extending from one edge of the plate.

In the drawings, Figure 1 is a perspective view of a necktie-holder, showing my new and original design. Fig. 2 is an end view of the same. Fig. 3 is a plan view.

Referring to the drawings, 1 designates an oppositely-tapered plate or body of approximately oblong shape, gradually decreasing in width from its ends to its center and pro-

vided at its terminals with tapering projections or tongues 2, located at the side edges of the plate or body. The tapering tongues or projections have approximately straight inner edges, and their outer edges are arranged at an angle to the adjacent side edges of the body or plate. Extending from one side of the plate or body is a transverse arm or hook 3, located near one end of the device and terminating short of the opposite side of the same. The body portion of the arm or hook is arranged parallel with the face of the plate, and its outer end is arranged at an angle to the same.

What is claimed is—

The design for a necktie-holder herein shown and described.

In testimony that I claim the foregoing as my own I have hereto affixed my signature in the presence of two witnesses.

DOD HASLUP.
